DRIER

John R. Spellacy, Burlingame, Calif., assignor to
 Hercules Powder Company, Wilmington, Del.,
 a corporation of Delaware

Application August 20, 1937, Serial No. 160,165

4 Claims. (Cl. 34—34)

This invention relates to driers, and particularly to driers of the dehydrating type.

The object of the invention is to provide an apparatus which is simple in structure and efficient in operation for drying or dehydrating various materials, and especially adapted to handle any dry bulk material, such as casein or lacto-¹⁰rine (milk curd), grain, flours, meals and the like.

A further object is to provide an apparatus of the nature referred to wherein the material to be handled, while moving in one direction in loose, comminuted, disintegrated or dispersed form is subjected to the action of air drying currents moving in the opposite direction whereby said material receives a uniform drying action throughout its bulk.

A further object is to provide an apparatus of the character and nature referred to wherein provision is made to subject the material to a continuous or sequentially continuous cycle of movement in loose bulk condition while being subjected to the drying action of air currents, heated or otherwise, until the moisture content of the material is reduced to the desired point.

A further object is to provide means in a drying apparatus of the nature and character referred to wherein provision is made to subject the material in its loose, comminuted, disintegrated or dispersed condition to the action of means to prevent or retard the development of germ growth or other bacterial, fermenting, or similar deleterious action.

A further object is to provide means whereby any lumps or chunks that may exist or be formed in the material during or preparatory to the drying operation, are efficiently broken up and dispersed so that the particles composing the material throughout its bulk and in its loose, comminuted, disintegrated and dispersed condition will be uniformly acted upon by the drying currents, or the germ retarding means, or both.

Other objects of the invention will appear more fully hereinafter.

The invention consists substantially in the construction, combination, location and relative arrangement of parts, all as will be more fully hereinafter set forth, as illustrated in the accompanying drawing, and finally pointed out in the appended claims.

The single figure of the drawing is a vertical central sectional view, somewhat diagrammatic, of an apparatus embodying the principles of my invention.

The methods at present in extensive use for

drying various materials in bulk, such as grain, flour, meals, and the like, and especially those practiced in drying casein or lacto-¹⁰rine (milk curd), and similar material, are not only crude, inefficient and expensive, but they also fail to secure a uniform drying action throughout the bulk of the material, through lack of desirable control or proper handling of the material and proper and uniform application of the drying medium.

It is among the special purposes of my present invention to provide an apparatus and method of operation which is efficient and whereby materials in bulk may be expeditiously and automatically handled and dried in bulk and in a ¹⁵ manner that enables the drying medium to reach all particles of the bulk material and exert a uniform drying action thereon, while at the same time preventing or at least retarding any bacteria or germ development within the body of the material.

In accordance with my invention I propose to cause the bulk material to be dried, and in loose, disintegrated and dispersed condition, to move in one direction while being subjected to the action of a drying medium, such as air currents, moving in the opposite direction in such manner that all particles of the material are subjected to the drying action of the drying medium, and I propose to subject the material to repeated ²⁰ and sequential dispersion and movement while being acted upon by the drying medium until the desired stage of dryness thereof is attained.

I also propose, in accordance with my invention, to control the dispersion and the speed of ²⁵ movement of the bulk material, and of the flow through the loose dispersed and disintegrated bulk thereof, of the cooling medium.

I also propose to subject the bulk material in its loose, dispersed and disintegrated condition, ³⁰ and during the drying operation, to the action of means to retard or prevent the development or action of injurious bacteria or germs.

And I propose to accomplish these operations under conditions of control and observation ³⁵ which insure efficiency, speed and uniformity of results throughout the entire bulk or mass of the material under treatment.

The operations above indicated may be carried out in many different types and forms of apparatus. While I have shown and will now describe one type or form of apparatus as an embodiment of my invention, capable of and adapted to efficiently carry out my invention, it is to be understood that said apparatus is illustrative of ⁴⁰ ⁴⁵ ⁵⁰

the principles involved, and my invention, in its broadest scope, is not to be limited or restricted to the specific details of structure shown and described.

5 In the arrangement shown I provide a vertically disposed casing 1, constituting a drying chamber, which may be of any desired size, height, or cross-sectional shape. The material to be handled, such, by way of illustration, as casein or 10 milk curd, is fed in bulk into the drying chamber at any convenient point, preferably at or near the lower end or base thereof, and in any suitable way. In the illustrative arrangement shown, the bulk material in the case of milk curd, for 15 example, is supplied into the drying chamber from the curd mill 2, which initially breaks up the material. This feed may be accomplished in any desired manner as, for example, by means of a screw conveyor 3, which delivers the bulk material to a point centrally of the drying chamber. From this point of delivery the material is elevated to the top of the drying chamber and is there scattered or dispersed in all directions into the chamber and permitted to fall by gravity 20 through the chamber to be collected at the bottom for elevation and dispersion again, if necessary, and finally to be withdrawn, ground, sifted and packaged.

Any suitable elevating and scattering or dispersing means may be employed. I have shown 30 a simple and efficient arrangement for this purpose wherein a tubular member 4 is vertically disposed centrally of the drying chamber 1, and supported in place by suitable struts or braces 35 5. Disposed centrally and longitudinally through the tubular member 4 is a shaft 6, arranged to be rotated in any convenient way and at any desired or controlled speed, as, for example, by means of a motor 7. Carried by shaft 6 is a continuous 40 spiral screw conveyor 8. The material delivery conveyor 3 delivers into a cylindrical chute 9 arranged centrally of the drying chamber 1, at the bottom thereof, and screw conveyor 8 extends into this chute and receives the delivered material and feeds it vertically through the tubular member and out through the open top of the latter, where, by reason of the centrifugal action 45 of the screw conveyor, it is thrown, scattered and dispersed loosely in all directions annularly or 50 radially into the drying chamber, where it falls to the bottom. The lower end of the drying chamber casing 1 is formed into a cone 10, into which the falling material is collected and by which the collected material is directed again to 55 the elevator screw 8 for repetition, if necessary, of the elevating and dispersing operations. The lower end of the tubular member 4, in which the elevating conveyor works, extends into the cone portion 10 of the drying chamber, and is itself 60 flared into an inverted cone 11. If desired, and in order to maintain the elevator tube 4 filled with the material to be treated while the apparatus is in operation, the portion 12 of the screw conveyor which works in the flared portion 11 65 of the conveyor tube 4, and in the bottom portion 10 of the drier casing 1, is enlarged, as shown, as compared with the other portions of said screw conveyor. The material which collects in the cone portion 10 of the dryer casing 70 slides down the sloping surfaces of the cone 10 and the flare portion 11 of tubular member 4, and past the lower edge of the latter into the space in which the enlarged elevator screw portion 12 works, and into the chute 9, and is again elevated and dispersed, as before explained.

This cycle of operation is repeated as often as may be desired to reduce the moisture content of the material to the desired degree. In order to break up any lumps that may remain in the material which collects in the cone portion 10 at the bottom of the drying chamber, the portion of the conveyor shaft 6 which carries the enlarged feeder screw portion 12 is provided with radial breaker arms 13, having scraper end portions 14 which work between the lower edge of the 10 flare 11 and the adjacent inner surface of the cone 10, thereby not only breaking up any lumps of the material but also preventing clogging of the material in the upper portion of the cone 10. Should the material collect in the cone 10, too rapidly to be handled by the elevator, the feed of additional material into the drier chamber may be arrested until all of the material collected in the cone 10 has been dried and withdrawn.

To permit the withdrawal of the material the 20 wall of the cone portion 10 is provided with an opening which is controlled by a slide gate 15. By opening this slide gate the material will fall through the opening for removal, instead of being directed back to the elevator for further treatment.

If desired, or required, the dried material which drops through the opening controlled by slide gate 15, may be received in a pulverizing mill 16, and ground or pulverized. This mill, in 30 the illustrative arrangement shown, delivers into a chute 17 through which the ground or pulverized material may be returned into the receiving chute 9, and again elevated and dispersed for further drying action, should further drying be 35 necessary. The chute 17 is provided with an opening through its wall which is controlled by a slide gate 18. When this gate is opened the pulverized material is permitted to fall through onto a sifter 19, and sifted to the desired fineness, 40 and then sacked for shipment, as indicated at 20. Any lumps or large portions of material caught and retained by the sifter may be returned into chute 9 for further treatment through a passage indicated at 21. A baffle 36 may serve to prevent 45 the material from flowing from the pulverizing mill 16, into chute 9 when the gate 18 is open.

In order to break up any lumps of material that may be elevated and thrown out by the upper end of the rotating screw elevator, and to assist 50 in a thorough scattering and dispersion of the material, I prefer to employ spinning devices onto which the material is delivered by the elevator. These, in the illustrative arrangement shown, consist of rapidly rotating disks 22 carried by 55 shafts 23 mounted in the top cover of the drier chamber and extending into said chamber near and slightly below the upper end of the conveyor tube 4. These shafts may be driven at a high speed in any convenient manner, as, for example, 60 by means of belts operating on pulleys 24. The disks 22 may be plane or fluted or otherwise shaped so that as the material falls thereon sharp hammer blows will be delivered to any lump, and the material will be rapidly whirled off into the 65 interior space of the chamber and thoroughly scattered and dispersed therein.

As above explained, the material to be treated while falling through the drying chamber after being thoroughly scattered and dispersed in loose 70 bulk condition is to be subjected to the drying action of currents of drying medium, heated or otherwise, as may be desired. This may be accomplished in many different ways. I have shown a simple and efficient arrangement, as il- 75

lustrative of the principles involved, wherein a blower fan 25 delivers air through a heater 26 and pipe connections 27, 27 into the interior of the drier chamber 1 at various points in the height thereof. I prefer to so arrange the delivery ends of the pipes 27, as indicated at 28, as to deliver the air more or less tangentially into the drier chamber so as to impart an annularly swirling or centrifugal motion to the air currents 10 within the chamber. The air currents ascend through the chamber, and they encounter and pass through the falling mass of material, thoroughly permeating through the falling mass and subjecting every particle of the same to an uniform drying action. An outlet 29 is provided at the upper end of the chamber through which the ascending air currents pass or are drawn off. In order to disperse the air currents and to evenly 20 distribute the same throughout the interior of the drying chamber, I prefer to arrange suitable baffles 30 at the delivery ends of the air supply pipes 27. I have indicated by light arrows the travel upwardly of the air currents through the chamber and by heavy arrows the downward 25 travel of the material to be treated.

If desired the temperature of the heated air, where heated air is employed, may be regulated and controlled in any suitable or convenient manner. For this purpose I have indicated a thermostatic 31 applied to the exterior wall of the drying chamber, and designed to be connected by a control pipe, a portion of which is shown at 32, to the air heater 26 in the usual and well-known manner.

35 If desired the observation windows 33 may be provided at convenient points through the walls of the drying chamber so that the action going on inside of the chamber while the operation is progressing may be observed.

40 In order to prevent or retard any injurious or deleterious bacterial, fermenting or germ action in the material under treatment, I prefer to set into the walls of the drying chamber at various points violet ray lamps, indicated at 34, so that 45 the material under treatment and every particle and portion thereof, while in scattered and loosely dispersed condition, is subjected to the actinic action of the violet rays.

To afford access to the interior of the drying 50 chamber for cleaning out or other purposes I provide a suitable manhole 35 in the wall of said chamber.

From the foregoing description it will be seen that I provide an exceedingly simple, inexpensive 55 and efficient method and apparatus for drying loose bulk material wherein and whereby the material is quickly dried uniformly throughout its bulk to the desired stage of dryness, the operation being carried on continuously or in continuous sequence or cycle.

It is to be understood that many changes in 60 details may readily occur to persons skilled in the art without departure from the spirit and scope of my invention. I do not desire, therefore, to 65 be limited or restricted to the exact details shown and described.

What I desire to protect and claim by Letters Patent is:

1. Apparatus for drying loose, bulk materials, including a drying chamber, rotating discs at the top of said chamber whereby to scatter and disperse the material in said chamber, a tubular member vertically disposed centrally within said chamber, an elevator operating within said tubular member and delivering at its upper end through said tubular member on to said rotating discs, means to deliver the material to be treated into the lower end of chamber, and means to circulate drying currents upwardly through the chamber and the falling mass. 10

2. Apparatus for drying loose, bulk materials, including a drying chamber, rotating discs at the top of said chamber whereby to scatter and disperse the material in said chamber, a tubular member vertically disposed centrally within said chamber, an elevator operating within said tubular member and delivering at its upper end through said tubular member on to said rotating discs, a receiver at the lower end of the chamber to receive the scattered and dispersed material as it falls through the chamber, said receiver having means to return the material collected therein to the elevator, means to deliver the material to be treated into the lower end of chamber, and means to circulate drying currents upwardly through the chamber and the falling mass. 25

3. Apparatus for drying loose, bulk materials, including a drying chamber, rotating discs at the top of said chamber whereby to scatter and disperse the material in said chamber, a tubular member vertically disposed centrally within said chamber, an elevator operating within said tubular member and delivering at its upper end through said tubular member on to said rotating discs, a receiver at the lower end of the chamber to receive the scattered and dispersed material as it falls through the chamber, said receiver having means to return the material collected 30 therein to the elevator, said receiver also having a controlled opening to permit the material to be delivered from the chamber, means to deliver the material to be treated into the lower end of chamber, and means to circulate drying currents 35 upwardly through the chamber and the falling mass. 40

4. Apparatus for drying loose, bulk materials, including a drying chamber, rotating discs at the top of said chamber whereby to scatter and disperse the material in said chamber, a tubular member vertically disposed centrally within said chamber, an elevator operating within said tubular member and delivering at its upper end through said tubular member on to said rotating 50 discs, a mill at the base of said chamber adapted to disintegrate material to be dried and discharge the disintegrated material into the base of said chamber, a receiver at the lower end of the chamber to receive the scattered and dispersed material as it falls through the chamber, said receiver having means to return the material collected 55 therein to the elevator, said receiver also having a controlled opening to permit the material to be delivered from the chamber, and means to circulate drying currents upwardly through the chamber and the falling mass. 60

JOHN R. SPELLACY.
